(57) **CLAIM**

The ornamental design for an antibody protein analysis chip, as shown and described.

DESCRIPTION

FIG. 1 is a top perspective view of the antibody protein analysis chip showing my new design;

FIG. 2 is an enlarged partial view shown broken away thereof;

FIG. 3 is a back view thereof;

FIG. 4 is a cross section view taken along line 4—4 thereof;

FIG. 5 is a top view thereof;

FIG. 6 is a side view with the opposite side being a mirror image thereof; and,

FIG. 7 is a front view thereof.
